UNITED STATES PATENT OFFICE.

SAMUEL SELDEN, OF DENVER, COLORADO.

LIFTING JACK.

1,413,792.

Specification of Letters Patent. Patented Apr. 25, 1922.

Application filed March 22, 1921. Serial No. 454,363.

To all whom it may concern:

Be it known that I, SAMUEL SELDEN, a citizen of the United States, residing at Denver, in the county of Denver and State 5 of Colorado, have invented certain new and useful Improvements in Lifting Jacks, of which the following is a specification.

This invention relates to lever jacks of the single action type and its primary object is to provide in a jack of this character 10 a reversing mechanism which combines, simplicity, compactness and durability of construction with practicability, efficiency and convenience of operation.

With this object in view, my invention 15 consists in the construction, arrangements and combinations of parts fully disclosed in the following description taken in connection with the accompanying drawings which 20 illustrate an embodiment thereof.

In the drawings in the several views of which like parts are similarly designated,

Figure 1 represents an elevation of a 25 single acting lifting jack to which my invention is applied;

Figure 2, a vertical sectional elevation of the operating parts of the same showing my improved reversing mechanism in the 30 position it occupies when the jack is used to lift its load;

Figure 3, a section taken on the line 3—3, Figure 2;

Figure 4, a section similar to that of Figure 2 showing the reversing mechanism in 35 the position it occupies when the jack is used to lower its load, the two pawls which act upon the rack bar having been shown in the position in which the locking pawl is released from the rack-bar and the lifting 40 pawl is in engagement with the teeth thereof prior to its being lowered by upward movement of the operating lever;

Figure 5, a view similar to Figure 4 showing 45 the parts in the position they occupy after the lever has completed its upward movement;

Figure 6, a side elevation of the eccentric 50 adjusting member of the reversing mechanism, and

Figure 7, a view similar to Figure 2 showing 55 the adjusting member provided with an additional spring-member for forcing the lifting pawl into engagement with the teeth of the rack-bar when the jack is used for lifting its load.

Referring more specifically to the draw-

ings, the reference character 2 designates a standard of conventional form and construction in which a rack-bar 3 has a vertical sliding movement. A housing 4 on 60 the standard in which the parts of the lifting and reversing mechanism are cooperatively assembled is normally closed by a side plate 5 which is detachably fastened to the body of the standard by screws 6. 65

The lever of the jack consists as usual of a metal socket 7 which is fulcrumed on the standard through the medium of a transverse pin 8 and a wooden handle 9 which is fitted in the socket at the outer end 70 thereof.

The socket has as usual, two shoulders 10 and 12 to limit its movement in opposite directions by engagement with a corresponding part of the standard and the retaining 75 pawl hereinafter to be described, and it carries at its inner end the lifting pawl 13 which normally engages with the teeth of the rack bar.

The pawl 13 is pivotally supported at the 80 end of the socket through the medium of trunnions 14 which extend in correspondingly formed open seats thereof and it is positioned with relation to the rack bar to constantly engage the teeth thereof by force 85 of gravity.

A locking or retaining pawl 15 which in the operation of the jack supports the load on the rack-bar while the other pawl is being lowered is pivoted on the standard as 90 at 16 to enter the teeth of the rack above the point at which the lifting pawl engages. The retaining pawl is likewise positioned with relation to the rack bar to engage the teeth thereof by gravity and when the lever 95 is in a condition of rest, as illustrated in Figure 2 of the drawings, both pawls mesh with the teeth of the rack bar and thus cooperate to hold it in its adjusted position.

The reversing mechanism of the present 100 invention comprises a block 17 which by means of a laterally projecting pin 18 is slidably supported in a horizontal slot of a plate 19 which is fastened inside the housing of the standard in substantial parallel 105 relation to the before-mentioned closing plate 5.

An eccentric 20 rotatably mounted on the pin is held against displacement by a head 21 at the outer end of the same and it has 110 forwardly projecting thumb wings 22 inside an opening 23 of the cover plate 5 to per-

mit of its rotation for the purpose of sliding the block in the slot of the plate.

The eccentric to this end works in a ring 24 which at the end of a radially projecting arm 25 is pivotally mounted upon the plate 19. Pivotal connected on top of the sliding block is a dog 26 the downwardly extending head of which has a slanting surface 27 which in the operation of the reversing mechanism is engaged by a laterally projecting stud 28 on the lifting pawl, as will hereinafter be more fully described.

The dog which normally rests upon the upper surface of the block carries an upwardly curving leaf-spring 29 which when the reversing mechanism is in its operative position, cooperates with a stud 30 at the upper end of the retaining pawl and another leaf-spring 31 attached at the bottom surface 20 face of the block 17 is designed to engage with a second stud 32 on the lifting pawl. Both springs extend forwardly from the parts with which they are connected, with relation to the rack bar and the therewith engaging pawls and the lower spring has a reversely bent end portion 33 for its engagement with the respective stud 32 on the lifting pawl when the jack is operated to lower its load.

30. When the jack is used to lift the load, as illustrated in Figure 2 of the drawings, the sliding block is in its extreme forward position in which the dog resting upon its upper surface and the two springs are out 35 of the paths of travel of the respective studs 32, 28 and 30 on the two pawls.

With the parts thus positioned the downward movement of the lever causes the rack to be raised through the medium of the 40 lifting pawl while the lever is subsequently lowered and the pawl passes idly across the teeth of the rack, the latter is locked in its adjusted position by engagement with the retaining pawl.

45. It will thus be understood that during the operation of the jack as a lifting medium the springs of the reversing mechanism are inoperative and gravity is the only force relied upon to effect the operative engagement of the pawl with the teeth of the rack bar.

In order to reverse the movement of the rack bar for the purpose of lowering the load upon its top, the slide is by rotation 55 of the eccentric moved rearwardly to the position illustrated in Figures 4 and 5.

With the lever of the jack in its normal position of rest the adjustment of the slide causes the slanting surface 27 of the head 60 of the pivoted dog to ride across the upper stud 28 of the lifting pawl, thereby moving the dog upwardly about its pivot until its head rests upon the stud as shown in Figure 4.

65. The upward motion of the dog causes the

curved spring 29 to forcibly press against the stud of the retaining pawl, with the result that when by a slight downward movement of the operating lever the pawl is released from the weight of the load on 70 the rack-bar, the deflected spring under the law of restitution will cause the pawl to disengage the teeth of the bar and thereby permit of the bar being lowered with the lifting pawl when the lever is subsequently 75 raised.

During the downward movement of the pawl 13 its stud engages the reversely bent end portion 33 of the spring 31 while the dog 26 gradually reassumes its original position and thereby carries the spring away from the stud on the upper pawl and when the lever reaches the end of its upward stroke the spring 31 gradually deflected by the engagement of the stud 32 will disengage the pawl from the teeth of the rack bar while the upper pawl now entirely disengaged from the other spring falls into the same and thus sustains the load until by downward movement of the lever the parts 90 are restored to their original position and the above described operation is repeated.

It will thus be seen that during the lowering action of the jack the two pawls alternately sustain the load and are alternately 95 released from the teeth of the rack bar by the automatic action of the resilient members of the reversing mechanism.

In the construction illustrated in Figure 7, an additional spring member 35 is provided 100 preferably by extending the spring below the sliding block of the reversing mechanism at its rear end and bending first downwardly and then forwardly to engage the stud 32 of the lifting pawl when the reversing mechanism is in its inoperative condition.

The supplemental spring member pressing upon the pawl aids in maintaining it in engagement with the teeth of the rack bar. 110

Having thus described my improved reversing mechanism in the most convenient and practical form at present known to me, I desire it understood that variations in the construction and arrangement of the 115 parts thereof may be resorted to within the scope of my invention as defined in the hereunto appended claims.

What I claim and desire to secure by Letters-Patent is:

1. In a lifting jack, the combination of a rack-bar, a lifting pawl and a retaining pawl engaging the teeth thereof, a lever in operative relation to the lifting pawl, and a reversing mechanism comprising an adjustable member, means for its adjustment to a determinate position with relation to the pawls, and springs on said member normally disengaged from the pawls and adapted to engage with the pawls when the member is 130

in its adjusted position, to alternately lift them out of engagement with the teeth of the rack bar in the operation of the jack by movement of the lever.

- 5 2. In a lifting jack, the combination of a rack-bar, a lifting pawl and a retaining pawl engaging the teeth thereof, a lever in operative relation to the lifting pawl, and a reversing mechanism comprising an adjustable carrier, means for its adjustment to a determinate position with relation to the pawls, spring members on said carrier adapted to engage with the pawls when the carrier is in its adjusted position, to alternately lift them out of engagement with the teeth of the rack bar in the operation of the jack by movement of the lever, and a spring member on the carrier which in the normal position thereof, acts upon the lifting pawl 20 to maintain it in engagement with the rack.

3. In a lifting jack, the combination of a rack-bar, a lifting pawl and a retaining pawl engaging the teeth thereof and having laterally projecting studs, a lever in operative relation to the lifting pawl, and a reversing mechanism comprising an adjustable member, means for its adjustment to a determinate position with relation to the pawls, and springs on said member normally disengaged from the studs and adapted to bear upon the same when the member is in its adjusted position, to alternately lift the pawls out of engagement with the teeth of the rack bar in the operation of the jack 35 by movement of the lever.

4. In a lifting jack, the combination of a rack-bar, a lifting pawl and a retaining pawl engaging the teeth thereof, a lever in operative relation to the lifting pawl, and a reversing mechanism comprising a slidably mounted member, means for its adjustment to a determinate position with relation to the pawls, and springs on said member adapted to engage with the pawls when the member is in its adjusted position, to alternately lift them out of engagement with the teeth of the rack-bar in the operation of the jack by movement of the lever.

5. In a lifting jack, the combination of a rack-bar, a lifting pawl and a retaining pawl engaging the teeth thereof, a lever in operative relation to the lifting pawl, and a reversing mechanism comprising a sliding member, means for its adjustment to a determinate position relative to the rack, a pivoted dog on the block, disposed to be raised by engagement with the lifting pawl when the block is in its adjusted position, and springs on the dog and the member 55 adapted to engage respectively with the retaining pawl and the lifting pawl when the member is in its adjusted position, to alternately lift them out of engagement with the teeth of the rack in the operation of the jack by movement of the lever.

6. In a lifting jack, the combination of a rack-bar, a lifting pawl and a retaining pawl engaging the teeth thereof, a lever in operative relation to the lifting pawl, and a reversing mechanism comprising a sliding member, means for its adjustment to a determinate position relative to the pawls, a dog pivotally disposed on the member to be raised by engagement with the lifting pawl when the member is in its adjusted position, 70 and springs on the dog and the member adapted to respectively engage the retaining pawl and the lifting pawl when the member is in its adjusted position, to alternately lift them out of engagement with the teeth of the rack bar in the operation of the jack by movement of the lever.

7. In a lifting jack, the combination of a rack-bar, a lifting pawl and a retaining pawl engaging the teeth thereof and having laterally projecting studs, a lever in operative relation to the lifting pawl, and a reversing mechanism comprising a sliding member, means for its adjustment to a determinate position with relation to the pawls, a dog pivotally disposed on the member to be lifted by engagement with the lifting pawl when the member is in its adjusted position, a spring on the dog which in the raised position thereof presses upon a stud on the retaining pawl, to release the latter from the teeth of the rack bar while the bar moves downwardly with the lifting pawl, and a spring on the member pressing upon the stud of the lifting pawl to release the latter 100 from the teeth of the rack bar at the termination of its downward motion.

8. In a lifting jack, the combination of a rack-bar, a lifting pawl and a retaining pawl engaging the teeth thereof, a lever in operative relation to the lifting pawl, and a reversing mechanism comprising a sliding member, means for its adjustment to a determinate position with relation to the pawls, a dog pivotally disposed on the member to be lifted by engagement with the lifting pawl when the member is in its adjusted position, a spring on the dog which in the raised position thereof presses upon the retaining pawl to release it from the teeth of the rack-bar while the bar moves downwardly with the lifting pawl, and a spring on the member pressing upon the lifting pawl to release it from the teeth of the rack bar at the termination of its downward motion.

9. In a single action lifting jack, the combination with a lifting pawl and a retaining pawl having laterally projecting studs, of a sliding member, means for adjusting it to a determinate position relative to the pawls, a pivoted dog on the member adapted to be raised by engagement with the lifting pawl, a spring on the dog adapted to engage a stud on the retaining pawl in the raised 130

41
position of the dog, and a spring on the member extending in the path of a stud on the lifting pawl during downward movement thereof.

5 10. In a lifting jack, the combination of a rack bar, pawls engaging the teeth thereof, an operating lever, and a reversing mechanism comprising an adjustable member, means for its adjustment to a determinate 25 position with relation to the pawls, and springs on said member normally disengaged from the pawls and adapted to engage with the pawls when the member is in its adjusted position, to alternately lift them out 30 of engagement with the teeth of the rack 35 bar in the operation of the jack by movement of the lever.

11. In a lifting jack, the combination of a rack bar, pawls engaging the teeth thereof, an operating lever, and a reversing mechanism 20

nism comprising a slidably mounted member, means for its adjustment to a determinate position with relation to the pawls, and springs on said member adapted to engage with the pawls when the member is in its adjusted position, to alternately lift them out of engagement with the teeth of the rack-bar in the operation of the jack by movement of the lever.

12. In a lifting jack the combination of a rack bar, a lifting pawl and a retaining pawl engaging the teeth thereof, an operating lever, and a reversing device including a sliding carrier and slanting springs on the carrier normally disengaged from the pawls and adapted to engage with the same in an adjusted position of the carrier.

In testimony whereof I have affixed my signature.

SAMUEL SELDEN.
